UNITED STATES PATENT OFFICE.

JAMES FRASER LISTER AND HORACE WILL SMALLWOOD, OF BIRMINGHAM, ENGLAND.

AUTOMATICALLY-OSCILLATING ELECTRIC FAN.

Application filed May 20, 1927, Serial No. 192,985, and in Great Britain June 7, 1926.

This invention relates to automatically oscillating electric fans of the type in which the fan wheel, in addition to revolving on its axis, is caused by the rotation of the fan wheel spindle, through a speed reducing gear, to oscillate on two axes at right angles to one another. The fan wheel spindle revolves in the usual bearing of a cylindrical casing containing the motor, said casing having trunnions between its ends mounted to rock in the arms of a forked frame, which frame is mounted to swing, on an axis at a right angle to the rocking axis of the casing, upon a pivot of a fan pedestal. Therefore the automatically oscillating electric fan to which the invention relates is of the pedestal type adapted to rest upon a table or to be attached by a bracket to a wall, said pedestal comprising a base and a central stem projecting therefrom.

According to the invention the end of the stem is provided with outwardly and oppositely projecting arms, one to support the pivot for the swinging forked frame and the other for connection thereto of one end of a link whose other end is connected with a reducing gear actuated by the fan spindle. These arms curve upwardly and away from the pedestal, and that arm which forms a support for the pivot for the forked frame causes the fan wheel to be disposed at a distance from the stem of the pedestal, thus making it possible either to use a larger diameter of fan or to permit a fan wheel of normal diameter to be dipped through a wider arc. The upward curvature of the oppositely disposed arm makes it possible for that part of the casing at the rear of the rocking trunnions to swing between the two arms. The arms may be rigid parts of the stem of the pedestal or may be hinged to the upper end of said stem in order that said arms may be tilted relatively to the pedestal and then be clamped in such position. The essential feature of the invention is the provision of an arm projecting laterally from the stem of the base for the purposes described.

In carrying the invention into effect a reducing gear is mounted at the rear end of the casing and has a second short shaft, parallel with the fan wheel spindle, to which shaft one end of the hereinbefore mentioned link is connected, which short shaft and link are not new, per se, in oscillating electric fans.

The link may be adjustable as to length and be telescopic, in order to vary the extent of the combined oscillations.

The invention not only provides a pedestal type of fan in which the fan wheel may either be of larger diameter or, if of normal diameter, can oscillate to a greater extent or dip more than usual, but in which, when the fan is resting upon a table or the like, there is better balance of the entire fan and oscillating action.

The invention will be described with reference to the accompanying drawing, in which:

Fig. 1 is a side elevation of the complete fan.

Fig. 2 is a side elevation of the two arms and the forked frame carried thereby.

Fig. 3 is an end elevation of the two arms and forked frame as viewed from the left of Fig. 2.

The pedestal comprises a base *a* and a central stem *a*² projecting therefrom. This pedestal is suitable to rest upon a table or for attachment to a wall by a bracket in a well known manner.

The stem *a*² is provided at its upper end with two oppositely disposed side arms *c* and *d*, the former to support the pivot *e* for the swinging forked frame *f*, and the latter for connection to one end *g*² of a link *g*, to be hereinafter described.

The arm *c* curves upwardly and laterally and the arm *d* curves upwardly and away from the pedestal. The forked frame *f*, between the arms or forks of which the motor casing *h* is mounted to swing on the trunnions *i*, is mounted to swing as at *e* on the free end of the arm *c*. This serves to keep the fan wheel well away from the stem *a*² of the pedestal, making it possible either to use a larger diameter of fan wheel *x* than usual or to use a fan wheel of normal diameter and to permit it to oscillate to a greater extent or to dip to a greater degree on the trunnions *i* than it could if the forked arm were close to the stem *a*³, while the upward and lateral curving of the arm *d* enables that part *h*² of the fan casing *h* which extends to the rear of the rocking trunnions *i* to swing between the two arms.

The arms *c* and *d* may be formed as rigid parts of the stem *a*², but as shown in the drawings they are integral parts of a casting having ears straddling the end of the stem and

connected thereto by a tilting and clamping pin *j* in order that the arms *c* and *d* may be tilted upon the stem.

The rear end *h*² of the fan body *h*, into which the end *y*² of the fan wheel spindle *y* projects, contains a speed reducing gear. On the end *y*² of the spindle is a worm *l*, gearing with a worm wheel *m* on a short shaft *n* which is rotatable on an axis at a right angle to the fan wheel spindle. This shaft *n* carries another worm *o* to drive a worm wheel *q* on a second short shaft *r*, parallel with the fan wheel spindle. The rear end *r*² of the shaft *r* projects beyond the rear end of the casing *h* and is connected to one end of the link *g* by a hinge pin *s*.

The link *g* may comprise a pair of telescopic members clamped together in adjusted position by a set screw but acting as a rigid link after adjustment, the lengthening and shortening of said link varying the extent of the combined oscillations.

The end *g*² of the link is pivoted to a stud *t* which is mounted to revolve in an opening in the extremity *d*² of the arm *d*, and the revolution of the stud in said opening is resisted by the friction set up by a spring *u* mounted in the outer end of the stud and bearing against the arm *d*.

The casing *h* rocks upon the trunnions *i* in the forked frame *f*, which swings on the arm *c* at a right angle to the rocking of the trunnions, there being the usual balancing of the fan body, reducing gear, fan wheel, et cetera, upon the forked frame *f*.

It will be clear from the foregoing description and the accompanying drawing that the combined oscillations of the fan wheel in the two planes at right angles to one another are caused by the connection of the shaft *r* to the arm *d* through the link *g*, and that the other arm *c* forms a mounting for the swinging movement of the forked frame *f* at a distance from the stem *a*² of the pedestal, and that, during such oscillations, the rear end *h*² of the body gyrates between the two arms *c* and *d*.

A feature of the invention is that the stud *t*, arm *d*, and the disposition of the shaft *r*

in relation to the rear end *h*² of the casing, and the upward curvature of the arm *d*, makes it possible for the rear end of the casing to gyrate within reasonable limits as to the height of the fan.

The speed reducing gear may be provided with a friction clutch for throwing the gear out of action, as commonly used in oscillating fans of this type.

The invention also produces a fan of very neat design and construction and which may be used either as a table fan or as a wall fan.

Having now described our invention what we claim and desire to secure by Letters Patent is:—

1. A support comprising a pedestal, a member mounted on said pedestal and having a pair of arms one of which extends laterally from said pedestal, a second member mounted to oscillate on said laterally extending arm on an axis in a plane common to said arms and said pedestal, said second member having a pair of arms between which a casing may be mounted to rock on an axis at substantially a right angle to the axis of oscillation of said second member, the other of said first-mentioned arms having means for connection thereto of means for rocking a casing mounted between the arms of said second member and for oscillating said second member on its axis.

2. A support comprising a pedestal, a member mounted on said pedestal and having a pair of arms offset in opposite directions from said pedestal, a second member mounted to oscillate on one of said arms on an axis in a plane passing through said arms and pedestal, said second member having a pair of arms between which a casing may be mounted to rock on an axis at a right angle to the axis of oscillation of said second member, the other of said arms having means for attachment thereto of means for oscillating said second member and rocking a casing mounted between the arms of said member.

In testimony whereof we have affixed our signatures.

JAMES FRASER LISTER.

HORACE WILL SMALLWOOD.
